UNITED STATES PATENT OFFICE.

CHRISTIAN WILLIAM MEINECKE, OF JERSEY CITY, NEW JERSEY, AND DANIEL HOGAN, OF NEW YORK, N. Y., ASSIGNORS TO THE MEINECKE & COMPANY, OF NEW YORK, N. Y.

DESIGN FOR AN AIR-CUSHION.

SPECIFICATION forming part of Design No. 33,763, dated December 18, 1900.

Application filed November 19, 1900. Serial No. 37,069. Term of patent 14 years.

To all whom it may concern:

Be it known that we, CHRISTIAN WILLIAM MEINECKE, residing at Jersey City, in the county of Hudson and State of New Jersey, and DANIEL HOGAN, residing at the borough of Manhattan, in the city, county, and State of New York, citizens of the United States, have invented and produced a new and original Design for an Air-Cushion, of which the following is a specification.

This design consists in an air cushion or seat having a body part with parallel sides and shanks, an end opening or narrow passage being extended between the shanks to a center opening in the body.

The design is illustrated in the annexed drawings, in which—

Figure 1 is a plan view of the cushion. Fig. 2 is an edge view of Fig. 1.

20 The body of the cushion is shown at 1 with

parallel sides 2. The shanks 3 join or run to the body. The end opening or passage 5 between the shanks extends to a wider central opening or hole 6 in the body. The shanks are shown gradually widening toward their 25 free ends.

The design gives a striking and characteristic appearance.

What we claim as new, and desire to secure by Letters Patent, is—

25 The design for an air-cushion as herein shown and described.

In testimony whereof we have hereunto set our hands in the presence of two subscribing witnesses.

CHRISTIAN WILLIAM MEINECKE.
DANIEL HOGAN.
